UNITED STATES PATENT OFFICE.

SAMUEL PRIOR, OF TRENTON, NEW JERSEY.

HEEL-STIFFENER MACHINE.

SPECIFICATION forming part of Letters Patent No. 309,161, dated December 9, 1884.

Application filed November 19, 1883. (No model.)

To all whom it may concern:

Be it known that I, SAMUEL PRIOR, a citizen of the United States, residing at Trenton, in the county of Mercer and State of New Jersey, have invented a certain new and useful Improvement in Machinery for Molding Boot and Shoe Stiffeners, of which the following is a specification.

My invention is shown in the accompanying drawings, in which Figure 1 is a side elevation, and Fig. 2 is a top elevation, of my machine, and Fig. 3 is a stiffener formed thereon. Fig. 4 shows the outline shape of my rolls and a sectional shape of the form. Fig. 5 is a view 15 in perspective of the bed-plate, grooves, guide-block, and form. Fig. 6 is a top view of the same with the stay and rolls added. Fig. 7 is a vertical section of Fig. 5 on dotted line *x x*. Fig. 8 is a horizontal section of Fig. 6 on dotted line *1 1*. Fig. 9 is a perspective view of the slide, hollow block, plate, slots, and rolls. Fig. 10 is a vertical sectional view of Fig. 9, taken on one side of the center.

In the drawings similar parts are indicated 25 by similar letters of reference.

In Fig. 2, A is the bed-plate, and B frame attached to such bed-plate. C is a shaft with journals C', such journals bolted to the frame. Upon this shaft are four cams, D', D', D², and 30 D³. Upon the bed-plate, and firmly bolted thereto, is the form E. This form is shaped to correspond with the inner shape of the stiffener when finished. Moving freely in grooves A' in the bed-plate A is the slide F. This 35 slide F has on it, and bolted thereto or fastened by any appropriate means, hollow block F'. Upon the top of this block is a plate, F². This plate is rubber-cushioned; but for sake of clearness the cushion is not shown, and it may be omitted without changing the 40 character of my invention. In this plate F² are slots F³ F⁴, and in the slide F are corresponding slots. In these slots play the axes of two rolls, G G. These rolls are shaped to 45 correspond in shape with the sides of the form E, and are each provided with the collar G', as shown in Fig. 4.

Back of the form E, and moving freely in the hollow block F', is the stay H. On either 50 side of the rolls G are guide-blocks I. These blocks move in the oblique grooves I' I' in blocks I³ I⁴, bolted to bed-plate A. The stay

H is connected by rod H' with cam D². The slide F, carrying the hollow block F', plate F², and rolls G G, is connected by the rod F' 55 with the cam D³. The blocks I are connected by the rods I² with slides I¹ I⁴, which in turn connect with cams D' D'.

In Fig. 4 is shown the outline shape of one of the rolls G and the sectional shape of the 60 form E. In this figure, G' is the collar of the roll G.

In Fig. 5 is shown in perspective the bed-plate A, with its grooves A', the guide-blocks I I, and form E. In Fig. 6 is shown a top 65 view of the same mechanism, with the stay H and also the rolls G G added. In both Figs. 5 and 6, for the sake of clearness, the slide F is omitted.

In Fig. 7, which is a vertical section of Fig. 70 5, taken at the dotted line *x x*, and in Fig. 8, which is a horizontal section of Fig. 6, taken on the dotted line *1 1*, I have for the sake of clearness, omitted the oblique grooves I I and blocks I³ I⁴.

In Fig. 9 I show a perspective view of the 75 slide F, carrying the hollow block F' and plate F², provided with the slots F³ F⁴. This view also shows the rolls G G; and in Fig. 10 I show a vertical sectional view of Fig. 9, such 80 vertical sectional view being taken on a line a little to one side of the center of such Fig. 9. These Figs. 5 to 10, inclusive, show more clearly and in detail the parts of my machine which shape the stiffener. 85

The operation of this machinery is as follows: The various slides being retracted, thus leaving the form free, the stiffener is inserted and placed upon the form E. By the revolution of the shaft C and the action of the cam 90 D² the stay H is brought in contact with the stiffener on the head of the form and holds it in position. The shaft still revolving by the action of the cams D' D', and connecting-slides I¹ I⁴, and rods I² I³, the blocks I are moved in 95 their grooves a short distance nearer the form, and the shaft still revolving by the action of cam D³, the slide F is moved in its grooves A'. The rolls G G engage the stiffener, and the slide F F still continuing its motion, the rolls 100 G G are forced down the sides of the stiffener; the blocks I remain stationary, but the rolls engaging against them are forced by the continued movement of the slide F firmly against

the stiffener as they pass along its sides until they reach the end of the stiffener and the form of the rolls corresponding to the sectional form of the form E. The stiffener is thus equally 5 pressed by these rolls against the form E at all parts of the stiffener. This same operation also turns over and firmly presses the flange of the stiffener. This flange is composed of that part of the stiffener which projects above 10 the form, and is turned over by the collars G' of the rolls as the rolls pass down the stiffener. The stiffener having been thus formed by the continued motion of the shaft C and the operation of the cams D' D', the blocks I are 15 slightly retracted, the slide F is drawn back, and the stiffener remains upon the form, held only in place by its own shape and the stay H, and the shaft still revolving, this stay is then retracted, and the stiffener is by any appropriate means ejected from the form E completed 20 and ready for use without further operation.

What I claim as my invention, and desire to secure by Letters Patent, is—

- 25 1. In a machine for forming boot and shoe stiffeners, the stationary form E, in combination with the rolls G G, provided with the collars G' G', substantially as shown and described.
2. In a machine for forming boot and shoe 30 stiffeners, the stationary form E, in combination with the stay H and rolls G G, such rolls provided with the collars G' G', substantially as shown and described.
3. In a machine for forming boot and shoe

stiffeners, the form E, in combination with the 35 rolls G G and blocks I I, substantially as shown and described.

4. In a machine for forming boot and shoe stiffeners, the slide F, with its hollow block F', and plate F², provided with slots F³, in combination with rolls G G, substantially as shown 40 and described.

5. In a machine for forming boot and shoe stiffeners, the slide F, with its hollow block F', plate F², provided with slots F³, and rolls G G, 45 in combination with the form E, substantially as shown and described.

6. In a machine for forming boot and shoe stiffeners, the slide F, with its hollow block F', plate F², provided with slots F³, and rolls G G, 50 in combination with the form E and blocks I I, substantially as shown and described.

7. In a machine for forming boot and shoe stiffeners, the slide F, with its hollow block F', plate F², provided with slots F³, and rolls G G, 55 in combination with the form E and stay H, substantially as shown and described.

8. In a machine for forming boot and shoe stiffeners, the slide F, with its hollow block F', plate F², provided with slots F³, and rolls G G, 60 in combination with the blocks I I, form E, and stay H, substantially as shown and described.

SAMUEL PRIOR.
